(57) **CLAIM**

The ornamental design for an adjustable paddle shaft, as shown and described.

DESCRIPTION

FIG. 1 is a top, right front perspective view of an adjustable paddle shaft showing our new design;

FIG. 2 is a front elevational view thereof drawn to an enlarged scale;

FIG. 3 is a rear elevational view of FIG. 2;

FIG. 4 is a top plan view of FIG. 2;

FIG. 5 is a bottom plan view of FIG. 2;

FIG. 6 is a cross-sectional view thereof taken in the direction of arrows 4-4 in FIG. 4;

FIG. 7 is a second top, right front perspective view of FIG. 1;

FIG. 8 is a right front perspective view drawn to the scale of FIGS. 2 through 6; and,

FIG. 9 is an exploded perspective detail view drawn to an enlarged scale with respect to FIGS. 2 through 6.

The structural features depicted by broken lines in the drawings have been shown for the purpose of illustrating portions of the adjustable paddle shaft that form no part of the claimed design.
